UNITED STATES PATENT OFFICE.

OSCAR T. ROSS, OF GOLDFIELD, NEVADA, ASSIGNOR OF ONE-HALF TO WARD HILDRETH, OF CHICAGO, ILLINOIS.

FLYING-MACHINE.

1,082,769.

Specification of Letters Patent.

Patented Dec. 30, 1913.

Application filed February 13, 1909. Serial No. 477,515.

To all whom it may concern:

Be it known that I, OSCAR T. ROSS, a citizen of the United States, residing at Goldfield, in the county of Esmeralda and State 5 of Nevada, have invented certain new and useful Improvements in Flying - Machines, of which the following is a specification.

My invention relates to a flying machine, and has for a principal object to provide a 10 flying machine of new and improved construction, which shall be much less liable to be affected by wind than any of those which are now being experimented with; which shall be more easily governed while underway 15 and also in starting and stopping; and which in other respects will be safer and less liable to derangement and accident than the known types of flying machines.

One principal object of my invention is 20 to apply the gyroscope principle to the construction of flying machines. In carrying out this idea I provide a sustaining member having an extended surface or surfaces, which member is rotatable and adapted to 25 stand, when the machine is under power, at somewhat of an inclination from the horizontal, and driving means on the car for rotating such sustaining member. This construction might be applied to a variety of 30 kinds of flying machines, of the heavier-than-air as well as lighter-than-air types, and so as to constitute the sole sustaining means or an auxiliary sustaining or steady- 35 ing means. This sustaining member might be constructed in a variety of ways. I have shown a machine having a single, circular, rotatable plane which constitutes the sole sustaining means of the airship, as I consider that my invention is best embodied in a 40 monoplane machine of that sort.

The invention has for a further object to provide for the guiding of the machine in rising and falling by shifting the relative positions of the car and the sustaining member, my invention contemplating hanging the car to the sustaining member by a pivoted connection.

The invention is for a further object to 50 provide cushioning or elastic means on the bottom of the car which will assist in stopping and starting the machine, these devices being particularly suitable for use upon a flying machine such as I show, but being nevertheless adaptable for use upon machines of entirely different types.

The invention has for further objects such new improvements in the construction of flying machines as will be described in the following specification and particularly set forth in the claims appended thereto.

A preferred embodiment of my invention is illustrated in the accompanying drawings, wherein—

Figure 1 is a side elevation of the machine in the air. Fig. 2 is a sectional plan view 65 taken below the plane. Fig. 3 is a partial side elevation illustrating the construction of the car. Fig. 4 is a sectional plan view of this part of the machine. Fig. 5 is an end elevation. Fig. 6 is a plan view of the driving connection for the plane, parts being omitted for the sake of clearness of illustration. Fig. 7 is a vertical sectional view of these parts. Fig. 8 is a side elevation of the driving pulley. Fig. 9 is a cross-section 75 on line 9—9 of Fig. 8, looking in the direction of the arrows. Fig. 10 is a sectional plan taken on line 10—10 of Fig. 7. Fig. 11 is a diagrammatic view of the machine illustrating the adjustment between the plane 80 and the car; and Fig. 12 is a perspective view of the machine.

Like characters of reference indicate like parts in the several figures of the drawings.

Referring to the drawings, 15 represents 85 the flooring of the car, 16 the forward frame-work carrying the shafts 17 of the propellers 18. The propellers are preferably arranged so that they drive the air up against the rotating plane (to be described 90 hereafter), as shown in Fig. 5.

The motor, which may be of any desired type, is represented by 19. On its main shaft 20 it carries a pinion 21, which meshes with a pinion 22 on a shaft 23. On shafts 20 95 and 23 are driving pulleys 24 connected by belts with pulleys 26 on the propeller shafts 17. Any other means might be devised for driving the propellers in opposite directions to each other.

27 is the rear frame which sustains the rudder 28 of any useful type. I have shown the rudder attached to a shaft 29, carrying a pulley 30, over which passes the belt 31, the ends of which are attached to the steering lever 32, provided with the hand wheel 33. The particular construction of these parts is not essential to my invention.

The rotating plane may be constructed in a variety of ways and of a variety of ma- 110

terials. I have shown it as consisting of cloth 34, braced and sustained by the radial arms 35, attached to the sleeve 36. The arms 35 are preferably braced by diagonal braces 37, which are attached to a hub 38. The plane 34 turns on a shaft 39, preferably on ball-bearings. On the upper end of shaft 39 is a cone 40, balls 41 being interposed between the cone and hub 38. Integral with 10 the hub 38 is a sleeve 42, on the other end of which is a hub 43 which surrounds a cone 44 fixed on shaft 39. Balls 45 are interposed between the hub and the cone. Any other 15 sort of anti-friction bearings might be employed. It is important that the plane turn as easily as possible.

In order that the plane may be collapsed for the purpose of easy transportation, although this is not essential, I have provided 20 hinges 46 between the braces 37 and hub 38, and similar hinges 47 and 48 between, respectively, the braces and the radial arms 35, and between the radial arms and sleeve 36. The sleeve 36 can slide on sleeve 42 to 25 collapse the plane. It is shown as held in proper position by means of set screws 49 which extend into perforations in the sleeve 42. In order that the structure be strengthened at the ends of the radial arms, where 30 the greatest strain is likely to come, the sleeve 42 is preferably provided with feathers 50, and the sleeve 36 with corresponding 35 slots.

The shaft 20 of motor 19 carries the pulley 35 51, and this pulley drives, by means of belt 52, a pulley 53 on a shaft 54, supported on the frame-work of the car. On this shaft is a beveled gear 55, meshing with a beveled gear 56, which latter meshes with a beveled 40 gear 57 on hub 43. By this means the plane 34 may be rotated. Any other form of driving device might be employed.

The car is hung from the plane, and preferably the connection between the two is 45 such that their angular position with regard to each other may be shifted. By this means the rising and descending of the machine may be controlled. I have shown the shaft 39 provided with trunnions 58, 59, the latter of which is extended so as to carry the beveled gear 56. These trunnions are carried in bearings on the box 60, supported upon the standards 61 from the flooring of the car. Shaft 39 has the extension 62 provided 55 with a fork 63 extending over the pin 64 of the follower 65, carried on the screw 66, which latter is provided with the hand-wheel 67. By this means the angular relationship between the car and the plane may 60 be varied, resulting in the shifting of the center of gravity of the car with respect to the axis of rotation of the plane, whereby the inclination of the plane from the horizontal may be varied.

It will be understood that the gyroscopic

action of the rotating plane is to resist any change of inclination of the plane. Consequently when the shifting mechanism is moved, the tendency is to tilt the car to a position out of the horizontal. This shifts 70 the center of gravity of the car and so, of course, changes the center of gravity of the entire machine, with the result that, as the machine adjusts itself to this changed condition, the relation of the plane to the horizontal is correspondingly changed. 75

I preferably construct the driving connection between the motor and the plane so that the plane may continue to rotate after the motor has been stopped and with least 80 possible friction. To this end, pulley 53 is constructed as shown in Figs. 8 and 9. Shaft 54 has keyed to it a collar 68 provided with notches 69, 69 which are engaged by dogs 70, 70, held in place by springs 71, 71, which 85 dogs are pivoted to pulley 53 which is loose on shaft 54. Any other form of clutch accomplishing the same results might be substituted for the one described.

I, preferably, provide the machine with 90 yielding supporting or guiding devices of sufficient elasticity to counterbalance in part the weight of the machine and which facilitate and guide the machine in starting and stopping. At the forward end of the car is 95 a shaft 72 to the opposite ends of which are secured the coil springs 73, and attached to these springs are legs 74, preferably, somewhat curved at the ends as shown at 100 75. At the rear end of the car is a shaft 76 which carries the coil spring 77 to which is attached the single leg or tail-piece 78, preferably, somewhat longer than legs 74. Straps 79 limit the forward movement of legs 74, and a similar strap 80 limits the movement 105 of the tail-piece 78. The position of these legs when the machine is in the air and about to alight is shown in Fig. 1. When the machine is at rest, the legs take the position shown in Fig. 3. In order to be able to take 110 off the tension from the springs when the machine is at rest, shafts 72 and 76 are arranged to rock in suitable bearings and are provided, respectively, with rock-arms 81 and 82, these arms being connected by means, 115 respectively, of rods 83 and 84, with an operating lever 85 which may be adjusted in the familiar manner upon the toothed sector 86.

In order that the motor may be disconnected from the propellers while still remaining connected up with the plane, so as to keep the plane in rotation, I provide a clutch 87 on the part of the motor shaft carrying the driving pulley for the propeller shafts. This clutch may be of any ordinary construction and is shown as operated by the handle 88.

The operation of the machine is as follows: In making a start the motor is set in 130

operation so as to drive the propellers and rotate the plane 34. The plane is set at an inclination to the horizontal, the pressure of air as the car moves forward, causes the 5 machine to rise from the ground as in the case of any aeroplane. The function of the legs 74 and tail-piece 78 is to assist the machine in rising, with a maximum of support at the start, the support and the friction between legs and ground lessening as the car rises. They also guide it and lessen the wobbling likely to occur before the machine gets under way. After the front legs have 10 left the ground, the longer tail-piece is still 15 in contact with the ground and helps to support and steady the machine. The rotation of the plane keeps the machine substantially level, even in a strong wind, thus overcoming one of the chief difficulties which have 20 stood in the way of the successful operation of aeroplanes. When the machine is flying on a level, the plane must be somewhat inclined from the horizontal. When it is rising the inclination must be greater. When 25 descending, the plane may stand in a substantially horizontal position, the car gradually descending as the speed of the propellers is lessened. These changes may be effected by means of the hand-wheel 67 on screw 66. 30 The effect of manipulating screw 66 is to shift the center of gravity of the car in relation to the rotation of the plane, and such a shifting brings about a change in the angular position of the plane with respect to 35 the horizontal. The machine may be steered from right to left with the ordinary rudder. The propellers which are preferably two in number are arranged under the plane, and preferably rotate so as to drive the air toward the plane rather than away from it. 40 When the motor stops, either from accident or intentionally, the plane continues to rotate by its own momentum, thus keeping the machine steady, on the gyroscopic principle, 45 as it slowly descends to the ground. Indeed, the operator might, in case of accident to the motor, keep the plane in rotation by a crank 56^a on gear 56. When the machine comes near the ground, the tail-piece 78 is 50 first to touch the ground. This guides the machine to a certain extent and its increasing friction with the ground acts as a drag or brake, and eases the descent. The front legs 74 next come into play, adding to the 55 cushioning, braking and guiding effect of the tail-piece. The increasing tension of the springs as the legs and tail-piece are folded backward by the descent of the car gradually increases this braking and cushioning effect. 60 As soon as the car comes to rest, the tension on the springs 73 and 77 is removed by moving the lever 85 and the car rests solidly on its flat base, so as not to be readily upset by the wind. As a further protection, 65 the plane can then be folded if desired.

I do not limit myself to the exact devices, constructions and arrangements shown and described as modifications might be devised which would come within the spirit of my invention as defined by the claims.

70

I claim:

1. The combination with a flying machine, of a rock-shaft at the forward end of the machine, a pair of elastically mounted legs on said rock-shaft, a rock-shaft at the rear end of the machine, an elastically mounted leg on said rock-shaft, which is longer than the forward legs, and means for limiting the forward movement of the legs.

75

2. The combination with a flying machine, of a rock-shaft at the forward end of the machine, a pair of elastically mounted legs on said rock-shaft, a rock-shaft at the rear end of the machine, an elastically mounted leg on said rock-shaft which is longer than the forward legs, means for 80 limiting the forward movement of the legs, and operating means for rocking said shafts so as to put said elastically mounted legs under tension or to relieve the tension 90 thereof.

85

3. The combination with a flying machine, of a plurality of braking and cushioning devices adapted to successively engage the ground with gradually increasing 95 friction so as to retard the forward movement of the car as the machine comes to rest.

95

4. The combination with a flying machine, of a plurality of retarding and cushioning devices arranged to successively engage the ground with increasing tension as the machine comes to rest, and means for throwing said devices into and out of operation at will.

100

5. The combination with a flying machine, of a plurality of means for affording a yielding support to the machine when at rest on the ground, but with decreasing efficiency as the machine rises, said devices 110 being arranged to successively leave the ground as the machine rises.

105

6. The combination with a flying machine, of a spring actuated leg adapted to engage the ground under more or less compression as the machine is nearer to or farther from the ground, and means for throwing the spring actuating said leg into or out of operation at will.

115

7. The combination with a flying machine, of a plurality of spring actuated legs adapted to engage the ground under more or less compression as the machine is nearer to or farther from the ground, and means for throwing the spring actuating said legs into 120 or out of operation at will.

120

8. The combination with a flying machine, of a plurality of spring actuated legs adapted to engage the ground under more or less compression as the machine is nearer 125 to or farther from the ground.

130

4
to or farther from the ground, and means
for throwing the spring actuating said legs
into or out of operation at will, said legs
being arranged to successively engage or
5 leave the ground as the machine descends
or rises.

9. In a flying machine the combination
with a plane, of a car carried below the
plane, a rigid leg at the forward end of the
10 car, a spring on which said leg is sustained

and which is adapted to be put under ten-
sion when the leg comes into contact with
the ground, a longer rigid leg at the rear
end of the car, and a spring sustaining said
leg.

OSCAR T. ROSS.
